DAM AND METHOD OF MAKING THE SAME

Frederick W. Scheidenhelm, Kew Gardens, N.Y.; Jean Wolff, executrix of said Frederick W. Scheidenhelm, deceased

Filed Nov. 13, 1957, Ser. No. 696,105

4 Claims. (Cl. 61—30)

This invention relates to the art of structures, such as dams, which are to be subjected to the pressure of a body of water. The invention pertains, more particularly, to constructions embodying such structures and to the method of making the same.

The primary object of the invention is to provide an improved rock fill dam which, in actual use, has afforded and, in prospective uses, will afford substantial economies compared with known rock fill dams.

Another object of the invention is to provide a dam or similar structure having improved and simplified features of construction.

A further object is the provision of a dumped rock fill dam characterized by a substantially water impermeable and flexible deck consisting only of asphaltic concrete which is disposed directly on the upstream face of the rock fill.

It must be borne in mind that a dam, the body of which is comprised solely of rock fill, requires a diaphragm or membrane which covers the upstream face of the rock fill and which is hereinafter referred to as a "deck."

It has been ascertained that, in the construction of a dam of this invention, it is not necessary to use any material other than rock and asphaltic concrete, together with, if circumstances require, a relatively minor amount of asphaltic cement or some other suitable binder.

The rock required for the dam of this invention is preponderantly such as constitutes the gross product of quarrying and consists to only a minor extent of rock or stone which has been submitted to the mechanical process of crushing. Moreover, the rock is placed by the simple and least costly process of dumping from automotive trucks, skips manipulated by derrick or cable-way, conveyor belts or any other suitable means. Only a minor amount of spreading is required even for the upstream surface portion of the rock fill, so that that fill may serve as a base, as hereinafter described.

One of the important features of the invention is that there is not required the customary placing by hand, or by derricks, cranes or other mechanical means, of selected rocks in the upstream portion of the rock fill in order that the latter may be adapted to the superposing of the deck thereon. Herein lies a major economy resulting from this new type of rock fill dam, especially as compared with the customary type, which uses a deck made of Portland cement concrete, whether plain or reinforced, for the reason that the latter type is usually, and as a matter of practical necessity, provided with a planar and sloping base of generally large, carefully placed rocks or stones upon which such a deck is formed.

Inasmuch as the function of the deck of a rock fill dam is to impound water, it must be watertight, i.e., impervious or impermeable to water. In addition, the deck needs to be sufficiently flexible to be self-adjusting to the settlement which normally occurs in any rock fill dam. Also, the deck should be constructed of a material which is durable and such that the construction may be rapid and that any requisite repair of the deck may be made without undue difficulty.

2

For the construction of such a deck, the present invention utilizes only asphaltic concrete. By asphaltic concrete is meant an appropriate mixture of asphalt, coarse stone aggregate (of size such as is used in Portland cement concrete) and fines (of stone or suitable earthly materials). The asphaltic concrete is placed in the form of a pavement comprised of one or more relatively superposed layers, the asphaltic concrete generally being hot when placed.

10 The customary rock fill dam having a deck made of Portland cement concrete, whether plain or reinforced and whether or not constructed in blocks or panels, does not afford all of the above-mentioned requirements and desiderata. In summary and in contra-distinction to the 15 customary rock fill dam, the dam of this invention, by virtue of having a deck made of asphaltic concrete, affords another major saving of cost.

In the interest of maximum economy and because the rock comprising the fill, when dumped as indicated 20 above, disposes itself naturally on a slope, the upstream surface of the rock fill, upon which the deck is to be superposed, must necessarily have a slope not steeper than the natural slope of the dumped rock (generally about 1 vertical on 1.3 to 1.4 horizontal). In this respect, 25 the practical aspects of placement of the asphaltic concrete deck pose no difficulty, for they make it desirable to use a somewhat flatter slope, usually not steeper than 1 vertical on 1.5 horizontal.

It has been found that, in order to attain the greatest 30 saving which may be realized from the dam of this invention, the placement of the asphaltic concrete to form the deck should, so far as feasible, be accomplished by means of paving machinery and other equipment which are of standard manufacture and used extensively

35 in the construction of asphaltic concrete surfaces of highways and of airplane runways. For this purpose, the upstream portion of the rock fill is so prepared that it will be stable and immobile under the movement thereon of loaded trucks and of heavy paving equipment, i.e., the 40 objective is that the use of such equipment will result in a minimum of disturbance or roughening of or undulations in the surface of said upstream portion.

It has been found that such stability and immobility in turn are attained by this new form of construction of 45 the rock fill and in particular of the upstream surface thereof.

The enumerated objects, together with the advantages attainable by the practice of this invention, will be readily understood by persons skilled in the art from the following detailed description and the accompanying drawings, 50 which, respectively, describe and illustrate a preferred embodiment of the invention.

In the drawings, wherein like reference characters denote corresponding parts in the several views:

55 Fig. 1 is a view, partly diagrammatic and partly in transverse cross section, of a dam constructed in accordance with this invention; and

Fig. 2 corresponds to Fig. 1 and is an enlarged view of an upstream portion of the dam.

60 Referring initially to Fig. 1, the dam illustrated therein comprises a base consisting essentially of rock fill which is generally denoted by the letter R. This rock fill, for the purposes of this description, may be considered as being disposed in three zones, namely, zone I, zone II and zone III. The first two zones comprise preponderantly rocks of large size, while zone III is composed of rocks which are of a smaller size and which in this description and the appended claims are referred to as "stones." Such rocks and stones are disposed by dumping in contra-distinction to laying or placing by hand or by mechanical equipment, such as derricks, cranes and the like. In the drawings, the rocks of zone

I are designated by numeral 1 and those of zone II by numeral 2. The stones of zone III are designated by numeral 3.

Zone I constitutes by far the greater part of the body of the dam. It is comprised preponderantly of large pieces of rock, weighing preferably $\frac{1}{2}$ ton to 5 tons or even more, depending largely upon the height and hence the size of the dam. It is desirable to limit the proportion of finer components of such rock, for the reason that, if the smaller pieces and particles lodge between the larger pieces, they are susceptible to crushing under the weight of the rock fill above, with the result that in time there may be undue settlement within and of the body of the rock fill. Therefore, the material of this first zone preferably contains not more than 10% by weight of 10 pieces and particles less than 4 inches in size.

Zone II lies upstream from and upon zone I and merges into the latter. The rock of zone II is dumped directly upon the naturally assumed upstream slope of the rock of zone I. Zone II has the two-fold function of (a) providing what may be termed a transition from zone I to zone III and (b) ensuring free drainage to the bottom or deepest portion of the dam.

The transition is not made gradually but rather abruptly. The same specification as to size of rock obtains throughout zone II. The maximum permissible size of the pieces of rock should be materially less than in the case of the zone I. Preferably the preponderant range of sizes of pieces should be from 4 inches to 30 inches. The material should be clean and well graded; the more nearly uniform the gradation, the better.

The object of free drainage is to ensure that there will be no entrapped seepage water which, regardless of source, upon drawing down of the impounded water, might by its pressure in the upstream direction damage the deck of the dam. To insure free drainage, this zone should be devoid of all pieces and particles of rock less than 3-inch size. The system of drainage is completed by providing along the floor of the valley or the stream bed a reliable means of drainage (not shown) from the upstream side of the rock fill, specifically connecting with the lowest portion of zone II and extending to and through the downstream face or toe of the dam.

The rocks of zone II occupy the space between the upstream slope, generally a natural slope, of zone I and a highly irregular surface which is somewhat short of the lower surface of the asphaltic concrete deck. The thickness of this zone may vary but should generally be not less than 5 feet and ordinarily need not be more than 10 feet. The approximate upstream surface defined by the rocks in this zone should be not more than 24 inches, preferably only 12 inches, short of, nor should any part thereof be nearer than 2 inches to, the lower surface of the asphaltic concrete deck.

The rocks comprising zones I and II of the rock fill may be angular, but the more rounded the edges of the pieces of rock, the less will be the undesired settlement of the rock fill after completion thereof.

Zone III consists of thoroughly compacted surfacing stones. The function of this zone is to fill the outer or upstream interstices of the rock of zone II and to extend such filling outward, to such extend that the outer surface of the zone III material has the same configuration, generally approximating a sloping plane, as the lower surface of the asphaltic concrete deck, which rests directly upon such outer surface. In general, the less the thickness of zone III the better.

Zone III is not watertight but rather is free draining to the greatest extent compatible with the attainment of the rigidity and immobility requisite for its service as a surface upon which the deck is placed. The outer interstices of the zone II rock are filled, not completely or solidly but, only in the sense that the zone III stones are tightly wedged into those interstices.

The requirement of maximum rigidity and immobility 75

makes it preferable, for optimum results, that the surfacing material in zone III be of crushed (hence angular) stones which are sound, hard and within the size limits preferably of $\frac{1}{2}$ and 4 inches. The zone III stones should be clean and devoid of pieces and particles of less than the indicated smaller size.

To the end of attaining the stability and rigidity requisite for the placing of the asphaltic concrete deck, particularly in the cases of the steeper deck slopes or of given material comprising zone III, it may be desirable, or even necessary, to apply to the surface stones a binder in liquid form, such as an appropriate type of asphalt or other suitable material. In any case, once the material comprising the third zone has been dumped and spread, it must be thoroughly compacted, preferably by a process involving vibration.

The cost of preparing the rock fill for placement of the asphaltic concrete deck is far less than the cost of preparing the base in the case of the customary type of rock fill dam which has a deck of Portland cement concrete.

As is indicated in the drawings, particularly in Fig. 2, the rocks 2 in the downstream portion of zone II project into the interstices defined by rocks 1 in the upstream portion of zone I. Similarly, downstream stones 3 of zone III are lodged in the interstices defined by the rocks 2 of the upstream portion of zone II. From this it is apparent that zone II merges with zone I while zone III merges with zone II. As is shown in the drawings, there is no clearcut line or surface demarcation between the rocks of zones I and II or between the rocks of zone II and the stones of zone III. The mean surface of demarcation between zones I and II is represented by dot-dash line a, while the mean surface of demarcation between zones II and III is represented by dot-dash line b.

The rocks of zones I and II and the stones of zone III may be placed in vertical stages or lifts, as they are referred to in the art. In the cases of dams of relatively great height, the placement of the rocks and stones in lifts is likely to be a matter of practical necessity.

In general, the dam of this invention should embody means for cutting off or preventing seepage from the impounded water through the ground or other foundation G upon which the base R rests. Such cut-off means should be at and in downward extension of the approximate intersection of the deck D and the foundation G. In Fig. 1 there is shown illustratively a cut-off wall C, which may be made of Portland cement concrete, asphaltic concrete or any other material known to the art. In the illustration, the deck D is shown as extending over the top of the cut-off wall C.

As has been stated earlier herein, deck D consists of only asphaltic concrete which is placed directly on the rigid and immobile upstream surface of zone III. Also, this deck is water impermeable. To obtain the latter property, the asphaltic concrete must be dense. The requisite density is attained by suitable compaction of the asphaltic concrete.

The asphaltic concrete may be placed in one or more layers, the total thickness depending largely upon what will be the overlying depth of impounded water. If the asphaltic concrete is placed in more than one layer, the joints within the upper layers should be staggered or offset in relation to the joints within any lower layer.

The procedure in placing deck D may, generally speaking, be the same as or similar to that followed in highway paving, with the exception that it may be necessary to rig cables from the equipment to winches or similar means located at a higher level, in order to move the equipment up and down the slope and to do so safely.

From the foregoing, it is believed that the dam or similar structure of this invention and the method of making the same will be readily comprehended by persons skilled in the art, without further description. It is to be borne in mind, however, that various changes in the structure herein shown and described and in the

method of practicing the invention, as outlined above, may be resorted to without departing from the spirit of the invention as defined by the appended claims.

What is claimed is:

1. In a dam or similar structure which is subject to the pressure of a body of water, a base comprising rock fill, said base comprising an upstream zone and a downstream zone, said downstream zone being of greater width than the upstream zone and comprising rocks at least 4 inches in size, said upstream zone consisting of a layer of angular stones which are of a size up to 4 inches and which are substantially immobile relative to each other, and a deck constituting the upstream face of the dam and consisting of a substantially water-impermeable membrane of asphaltic concrete, said deck being disposed directly on the upstream face of the base.

2. In a dam or similar structure which is subject to the pressure of a body of water, a base consisting of rock fill, said base comprising an upstream zone and a downstream zone, said downstream zone being of greater width than the upstream zone, at least 90% of the downstream zone consisting of rocks at least 4 inches in size, said upstream zone comprising a layer of angular stones which are of a size up to 4 inches and which are substantially immobile relative to each other, and a deck constituting the upstream face of the dam and consisting of a substantially water-impermeable membrane of asphaltic concrete, said deck being disposed directly on the upstream face of the base.

3. The method of making a dam or similar structure which is to be subjected to the pressure of a body of water, which comprises forming a rock fill base by the steps of randomly dumping rocks, at least 90% of which are at least 4 inches in size, to obtain the downstream

zone of the base and dumping on the upstream face of the downstream zone a layer of angular stones of a size not exceeding 4 inches, compacting said layer whereby to render the stones thereof substantially immobile relative to each other, and forming directly on the upstream face of said layer of stones a substantially water-impermeable membrane consisting of asphaltic concrete.

4. The method of making a dam or similar structure which is to be subjected to the pressure of a body of water, which comprises forming a rock fill base by the steps of randomly dumping rocks, at least 90% of which are at least 4 inches in size, to obtain the downstream zone of the base and dumping on the upstream face of the downstream zone a layer of angular stones of a size not exceeding 4 inches, compacting the layer of stones by subjecting the same to rolling whereby to render the stones thereof substantially immobile relative to each other, and forming directly on the upstream face of said layer of stones a substantially water-impermeable membrane consisting of asphaltic concrete.
